BLANK-HOLDER PRESS

Walter Ernst, Mount Gilead, Ohio, assignor to
 The Hydraulic Development Corp. Inc., Wil-
 mington, Del., a corporation of Delaware

Application December 11, 1939, Serial No. 308,594

8 Claims. (Cl. 113—45)

This invention relates to hydraulic presses and in particular to means and mechanism for operating blankholders on hydraulic presses.

It is particularly the object of this invention to provide means of operating and controlling a hydraulic press, and especially that part of the press dealing with blankholders.

It is an object of the invention to coordinate the operation of the hydraulic press with the operation of the blankholder and to operate both the press and the blankholder hydraulically in synchronism with one another.

It is an object of this invention to provide an independent source of hydraulic pressure for the blankholder cylinders, and means of regulating the application of that pressure to the respective cylinders of the blankholder.

It is a further object of this invention to provide means of balancing the pressure between the respective cylinders of the blankholder.

It is a further object to provide means of hydraulically operating and hydraulically timing a blankholder in connection with the hydraulic operation of a platen of a press.

It is a further object to provide a hydraulic press in which the hydraulic pressure for operating the platen piston in the main ram is solely supplied by a major source of hydraulic pressure without any diversion of that hydraulic pressure for operating a blankholder. It is an object to overcome the difficulties heretofore encountered in the art of utilizing a part of the major source of hydraulic pressure for actuating the piston, which diverted pressure was utilized for operating the blankholder.

It is an object of this invention to provide one source of hydraulic pressure for the operation of the platen and an independent pressure source for operating the blankholder, but timed and coordinated so as to operate in synchronism with the platen.

It is a further object of this invention to utilize the separate source of pressure for the blankholder to prefill the blankholder cylinders when the platen is elevated and to thereafter utilize the major pressure on the ram in the main cylinder so that when the platen is forced down to draw the metal, this same downward force will cause an increase of pressure in the blankholder cylinders so that the greater the pressure on the platen, there is proportionately greater coordinated application of pressure applied to the blankholder.

It is a further object in this connection to provide means of relieving the pressure in said blankholder cylinders as the platen descends in the course of the application of the drawing pressure on the metal being drawn.

It is a further object of this invention to provide means of increasing the pressure in the

blankholder cylinders to facilitate stripping as the platen is withdrawn and to utilize the separate source of hydraulic pressure for this purpose, and to utilize this blankholder pressure for stripping purposes as also the means of prefilling the blankholder cylinders prior to another stroke of the platen.

It is a further object to utilize the unloading valve system, which unloads the pressure source for the blankholder cylinders, for the additional purpose of adjustably determining the amount of the pressure in the blankholder cylinders during stripping.

One of the novel features of this invention is the utilization of two independent hydraulic systems, one for the platen and one for the blankholder, which operate in synchronism despite the fact that they are not controlled one by the other but independently operate, thereby eliminating the necessity for complicated controls.

Referring to the drawings:

Figure 1 is a diagrammatic vertical section through a metal drawing press, showing one form of hydraulic operating system of this invention for controlling the action of the blankholder.

Figure 2 is a vertical section through the press showing the parts in position at the start of the pressing or drawing operation.

Figure 3 is a similar view showing the parts in position during the stripping and prefilling operations.

Figure 4 is a horizontal section through the platen of the press shown in Figure 1, taken on the line 2—2 and looking in the direction of the arrows, and further illustrating the hydraulic operating system seen in Figure 1.

Figure 5 is a view similar to Figure 2, but illustrating a modified form of operating system wherein provision is made for adjustably determining the pressures in each of the blankholder cylinders;

Figure 6 is an enlarged vertical section of the pump unloading valve seen in Figures 1 to 3.

Referring to the drawings in detail, and particularly to Figures 1, 2 and 3, there is provided a main pressing plunger 1, having at its upper end a double-acting hydraulic piston 2. This piston reciprocates within a cylinder 3 according as pressure fluid is delivered to its upper pressing area, or to its lower pullback area. Fluid pressure for moving the piston 2 is generated by a pump shown diagrammatically at 4, this pump being of the variable delivery reversible type. One of the discharge ports of the pump is connected by the conduit 5 to the upper wall of the cylinder 3 for effecting the downward pressing stroke of the piston 2, and the other discharge port of the pump is connected by the conduit 6 to a port in the lower side wall of the cylinder 3 for effecting

the return stroke of the piston 2. The flow controlling element of the pump 4 may be shifted by any suitable manual or automatic means, such means being omitted from the drawings since they form no part of this invention.

The cylinder 3 is rigidly mounted in the head of the press, designated 1, this head being supported upon, and spaced from a base 8 by means of strain rods 9.

Attached to the pressing plunger 1 and moving integrally with it is the main platen 10, to which, in turn, is attached the upper member of a die shown in the drawings as the male member 11 adapted to mate with the lower member 12 of the die which is mounted upon the bed of the press. Within the platen there is formed a plurality of secondary pressing cylinders 13, these cylinders receiving pressure fluid from a secondary source for the purpose of exerting a clamping force through the plungers 14 to the blankholder platen 15. The plungers 14 may be attached by any suitable means, such as threads 16, to the blankholder platen 15. The blankholder platen is adapted to engage the workpiece, shown in the drawings as a flat blank 17, transmitting to the workpiece the clamping pressure generated in the blankholder cylinders 13, for the purpose of preventing the formation of tears and wrinkles.

As seen in Figures 1 to 4, pressure fluid to the blankholder cylinders 13 is supplied by the auxiliary pump 18 which is of the common vane or gear type having a constant displacement. This pump draws its fluid through the conduit 19 from the tank 20 and delivers it to an unloading valve, generally designated 21, through a conduit 22. Interposed between the valve 21 and conduit 22 is a flexible connection 23, shown in Figure 1. This connection is in the form of a stationary cylinder within which telescopes the conduit 22a, the latter being mounted, along with the valve 21, upon the press platen 10, and moving with it as it reciprocates in its pressing and return strokes.

Since the pump 18 is of the constant displacement type, fluid will at all times be delivered to the valve 21, from which it will be discharged in one of two directions, depending upon the requirements of the blankholder cylinders 13. If these cylinders are under relatively low pressure, which condition occurs at the beginning of a retraction stroke of the press, fluid will pass from the valve 21 into the conduit 24, past the ball check valve 25, into a common blankholder supply conduit 26, and finally through blankholder supply conduits 27 to the cylinders 13. If, on the other hand, the pressure within the blankholder cylinders is relatively high, such as occurs during a drawing operation, then the valve 21 will be actuated to exhaust through the line 28 and back to the tank 20. At this time the total delivery of the pump 18 will be by-passed or unloaded through the valve 21.

As shown in Figure 6, this valve consists of a valve body 29, having a bore 30, within which reciprocates a plunger 31. The plunger 31 is adapted to fit snugly within the bore 30 so that when it enters this bore, as shown in Figure 4, no fluid passage is permitted between the line 22a and the conduit 28. Surrounding the plunger 31, and located centrally of the valve body 29, there is provided an annular chamber 32, which at all times maintains fluid communication between conduit 22a and conduit 24. Toward its upper end, the plunger 31 is provided with a

shoulder 33, which, in response to fluid pressure within the annular chamber 34, urges the plunger upwardly in opposition to the compression of the spring 35. At one end this spring bears against the head 36 of the plunger 31 and at the other end against the retainer 37, the position of which is set by the conical end of the adjusting screw 38. This adjusting screw is threaded into the top wall of the spring barrel 39, and is locked in place by the nut 40. It will be readily apparent that different settings of the adjusting screw 38, by varying the compression of the spring 35, will require correspondingly different fluid pressures within the annular chamber 34, acting against the area presented by the shoulder 33, to lift the plunger 31 and consequently to open the passage between the incoming conduit 22a and the exhaust conduit 28. Pressure is communicated to the chamber 34 through the control conduit 41 from any one of the blankholder cylinders 13. The unloading of the pump 18 through the valve 21 is thus responsive to pressures within the cylinders 13, and these pressures, in turn, are determined by the setting of the adjustment 38 of the valve 21. At the entrance of the conduit 41 into the chamber 34, there is provided an adjustable needle valve 42, which, by presenting a choke or resistance to the fluid flow into or out of chamber 34, determines the reaction time of the valve 21.

Referring again to the modification of Figures 1 to 4, there is provided a conduit 43 leading from one of the blankholder cylinders to the intake port of a relief valve 44 and a safety valve 45. It is through this conduit that all fluid trapped within the cylinders 13 is exhausted. It will be observed that, because of the provision of the check valve 25 between conduits 24 and 26, fluid within the cylinders 13 cannot escape through said conduits, but must escape through conduit 43. It will also be observed, that in this modification, since all the blankholder cylinders are in open communication with one another through the supply conduit 26 and branches 27, no outlet, other than conduit 43, is necessary. Exhaust from the blankholder cylinders normally passes through the relief valve 44, and takes place during the pressing stroke when the blankholder 15 has exerted upon the work piece the maximum pressure permitted by a given setting of the adjustment 46 of the relief valve 44. The safety valve 45 is normally inoperative and acts only in the event of failure of the valve 44 to open, resulting in the development of excessive pressure in the blankholder system. The valves 45 and 46 are both of the usual type in which pressure fluid acts against a spring-loaded plunger, the valve spring opposing the fluid pressure in accordance with the setting of a screw-threaded adjusting nut. Both of the valves 44 and 45 empty into the conduit 47 which returns to the tank 20. As seen in Figure 1, there is provided in the line 47 a telescoping joint similar to the one shown in the pump discharge line 22, and provided for the same purpose, namely, to permit valves 44 and 45 with their piping to reciprocate with the platen 10 of the press. This telescoping joint is designated 48.

It will be noted by referring to Figure 1 that the lower surface of the blankholder platen 15 stands slightly in advance of the lower surface of the die member 11. The purpose of this arrangement is, according to common metal drawing practice, to permit the blankholder platen to engage the workpiece and to clamp it

under predetermined pressure before the work-piece is contacted by the upper die member. In this invention the exact spacing of the blankholder platen 15 relative to the upper die member 11 is controlled by the adjustment of spacing rods 49 which are fastened, as by threading, into the blankholder platen 15, and which are threaded at their upper ends to receive adjusting nuts 50, which act as stops against the upper surface of the main press platen 10, thus limiting the extent to which the pressure within the blankholder cylinders 13 may extend the blankholder platen 15 upon the retraction stroke of the press. The spacing rods 49 slide freely within bores 51 in the platen 10.

Operation

The operation of the press, having the circuit arrangement shown in Figures 1 to 4, is as follows. Let it be assumed that the press is idling; that is, that both the pump 18, and the main operating pump 4, are being driven by their respective motors, and that the platen 10 is standing stationary in its fully open position. This condition shown in Figure 1, obtains after the completion of a retraction stroke, and upon the shifting of pump 4 to its neutral position, by means of control apparatus, not shown. At this time, the blankholder cylinders 13 are filled with fluid, the pressure of which, in addition to the weight of the blankholder platen 15 and the parts mounted upon it, is holding the blankholder platen 15 in its fully extended position with the adjusting nuts 50 bearing against the upper surface of the main platen 10. The particular pressure existing within the cylinders 13 has been predetermined by the setting of the valve 21. Pressure within all of the cylinders 13 is identical because of their interconnection by means of the lines 26 and 27, and this pressure is communicated to the annular compartment 34 of the valve 21 through the control conduit 41. During the idling position of the press, now under consideration, this pressure within the cylinders is sufficient to move the plunger 31 of the unloading valve upwardly against the opposing spring 35, so that the total delivery of the pump 18 is being by-passed from the line 22a through the unloading valve to the line 28 and back to the tank 20. So long as the press continues to idle, this by-passing or unloading of the pump 18 will continue.

When the operator initiates a pressing cycle by actuating the controls to the pump 4 so as to deliver pressure fluid into the conduit 5, withdrawing fluid from the pullback side of the piston 2 through the conduit 6, the main pressing piston 2, ram 1, and main platen 10, will start their downward movement, carrying with them the upper die member 11 and the blankholder platen 15 with its plunger 14 and spacer rods 49. Valves 21, 44 and 45, being mounted upon the main platen, will also move downwardly carrying the piping associated with them, the telescoping joints 23 and 48 permitting this movement relative to the stationary piping while at the same time maintaining intact the hydraulic connection of the parts. During this downward traverse of the pressing members, and before the engagement of the work piece by the blankholder platen 15, the spatial relationship of this platen with the main press platen does not change from the idling position of these parts, the predetermined pressure in the cylinders 13 remaining at the same level, this pressure continuing to hold the

unloading valve 21 in its open position, and the pump 18 continuing to by-pass to the tank 20.

The condition just described obtains until the work piece is engaged. Since the blankholder platen precedes the die member 11, as determined by the setting of the adjusting screws 50, it first engages the work piece 17. Although this action brings the blankholder platen to rest, the main platen 10 and the upper die member continue to advance toward the work, perhaps at a decelerated rate as governed by the controls to the main pump 4. It is this relative motion between the main platen and the blankholder platen 15 which builds up the blankholder pressure within the cylinders 13 by carrying these cylinders downwardly over their respective plungers 14, these plungers having now become stationary. Since these blankholder cylinders have previously been filled with fluid along with the conduits leading to and from the cylinders, this telescoping motion of the cylinders over their respective plungers 14 causes pressure to be built up rapidly, and this pressure, acting upon the upper ends of the plungers, and being transmitted by them to the blankholder platen, results in the clamping of the margin of the workpiece against the lower die member 12. The maximum point to which this clamping force may be raised is determined by the setting of the adjusting nuts 46 of the relief valve 44. It will be recalled that pressure, trapped within the blankholder cylinders 13, may escape only by way of this relief valve through the conduit 43, due to the presence of the ball check valves 25 in the supply line to these cylinders. Consequently, upon the attainment of the desired pressure within the blankholder cylinders, further motion of the main platen 10 relative to the blankholder platen 15, will cause fluid displaced by the plungers 14 to escape through the relief valve 44 and to return to the tank 20 (for illustration of this action see Figure 2). Once this escape of fluid takes place, the pressure within the cylinders 13 will rise no higher, but, on the other hand, will be maintained at the levels reached. Since, in the modification shown in Figures 1 to 4, the several blankholder cylinders are in open communication with one another, the single relief valve 44 will serve to maintain all of these cylinders at identical pressure. This condition is applicable where the nature of the operation to be performed upon the workpiece 17 is such as to require equal clamping pressure at all points about the margin of the workpiece.

Appropriate blankholder pressure having been built up, the male die member 11 engages the workpiece 17 as the main press ram 1 continues to drive this die member toward the lower mating die member 12. As the workpiece 17 is pressed into the cavity of the die member 12, its marginal portion slips under the pressure of the blankholder platen to supply the metal necessary for the drawing operation; and upon the termination of this operation, the return movement of the press will be initiated either in response to the pressure built up above the main pressing area of the piston 2, or by the position reached by the die member 11. In either case, the control mechanism to the main pump 4 will be actuated so as to reverse the delivery of this pump causing it to draw fluid away from the pressing area of the piston 2 and to supply it to the pullback area. As to the action of the pump 18 and valve 21 during the actual pressing operation, it will be observed that, since the pressure within the cylinders 13 prior to this pressing operation was sufficient

to cause opening of the valve 21 and unloading of the delivery of pump 18, the higher pressures developed within these cylinders during the working stage are, of course, sufficient to maintain valve 21 and pump 18 in their unloading relation.

As soon as the return stroke of the press is begun, the function of the die 11 has been completed for one cycle. The blankholder platen, however, as illustrated in Figure 3, now enters upon the second phase of its function, namely, to serve as a stripper plate for removing the finished article as it clings to the male member 11 of the die. This stripping action of the blankholder platen 15 is brought about and controlled by a change of conditions within the cylinders 13. As the platen 10 starts upwardly and is lifted away from the blankholder platen 15, a rapid drop in pressure occurs within the cylinders 13, whereupon the relief valve 44 closes, and, for the first time in the cycle, the pump 18 begins to supply fluid to the cylinders 13. This latter event is due to the lowering of the pressure within the annular chamber 34 of the unloading valve 21 correspondingly with the lowering of pressure within the blankholder cylinders, and the consequent closing of the passage between conduits 22a and 28 by the compression of the valve spring 35. The output of pump 18 is thus no longer by-passed to the tank, but, instead, is utilized to perform the stripping action described above, and simultaneously, to prefill the blankholder cylinders 13 to the full extent permitted by the location of adjusting nuts 50 upon spacer rods 49, preparatory to the next pressing cycle. During the first portion of the return stroke of the press, the main platen 10 rises while the blankholder platen 15 remains stationary upon the margin of the workpiece, this separating action of the two platens being the result of the flow of pressure fluid from pump 18 into the cylinders 13. It is by causing this separation of the platens 10 and 15 that pressure fluid from the pump 18 results in stripping the work from the upper die member 11.

In connection with the stripping of the work piece and the prefilling of the blankholder cylinders, two advantages of the present invention over previous arrangements should be noted. The first of these concerns the widely varying stripping pressures demanded by different pressing operations. The inclusion of the unloading valve 21 in the present invention provides for meeting these demands by making available, through the setting of the adjusting screw 38, any stripping pressure up to the pressure capacity of the pump 18. The second advantage lies in the provision of pump 18 in addition to the main operating pump 4 for the purpose of providing stripping pressure in the blankholder cylinders and of prefilling these cylinders. In previous hydraulic arrangements, the pullback discharge of the main operating pump has been partly diverted to the blankholder cylinders to perform these functions. Since it is desirable for the opening stroke of the press to be effected without delay, such an arrangement has necessarily introduced a problem which can be solved only by supplying a main operating pump having greater capacity, with an attendant considerable increase in cost. By providing the simpler constant delivery vane or gear type pump 18 of this invention, the main operating pump is relieved of its stripping and prefilling functions, so that its full discharge may be devoted to effecting a speedy return of the press platen. Thus, a faster press is provided at lower cost.

After the stripping and prefilling functions have been completed by fluid pressure in the cylinders 13, there remains to the completion of the press cycle only the retraction of the blankholder platen 15 from its clamping engagement with the workpiece 17 and die member 12. This is accomplished by the contacting of the nuts 50 by the main platen 10 in its upward movement, the spacer rods 49 then lifting the blankholder platen. Platens 10 and 15 then move upwardly as a unit until suitable control means actuate the flow control element of pump 4 moving it to neutral position, at which time the return movement is terminated, and the press again stands in the idling state of Figure 1, in readiness for the beginning of another cycle.

In the modification shown in Figure 5 of the drawings, the hydraulic operating system associated with the blank holder cylinders 13 is similar to that shown in Figures 1 to 4, but provision is made therein for independent control of the pressure generated within the cylinders 13 during the pressing operation. This consists in placing, in the branch lines 27, separate ball check valves 25a for each of the blankholder cylinders; in providing separate exhaust conduits 43a for each of these cylinders; and in interposing between these exhaust conduits and the return conduit 41 separate relief and safety valves 44a and 45a. The check valves 25a, while permitting the flow of fluid into the blankholder cylinders from the pump 18, prevent the pressure developed in the cylinders during an actual pressing operation from being communicated to one another through the supply conduits 26 and 27 and thereby equalizing with one another. The precise pressure developed in each blankholder cylinder and confined within it by the associated check valve 25a, is determined by the setting of the manual adjustment of the associated relief valve 44a. It will be apparent that with this arrangement independent pressures may be generated within each of the several blankholder cylinders, and transmitted through the respective plungers 14 to the blankholder platen 15 for applying the varying clamping forces required by many metal drawing operations. The stripping and pre-filling actions in the modification of Figure 5 are identical with those in the modification of Figures 1 to 4. The control conduit 41 to the unloading valve 21 may be connected to any one of the blankholder cylinders 13.

It will be understood that I desire to comprehend within my invention such modifications as come within the scope of the claims and the invention.

Having thus fully described my invention, what I claim as new and desire to secure by Letters Patent, is:

1. In combination in a hydraulic press, a platen, ram and main cylinder, a source of hydraulic fluid pressure for exclusively supplying pressure fluid to said ram for reciprocating said platen, a plurality of blankholder cylinders in said platen, a blankholder, pistons on said blankholder arranged for reciprocation in said blankholder cylinders, a second and independent source of hydraulic fluid pressure for exclusively supplying pressure fluid to said blankholder cylinders during the retraction stroke of said platen to completely fill said cylinders and provide a constant positive pressure therein to maintain said blankholder separated from said platen.
2. In combination in a hydraulic press, a platen,

ram and main cylinder, a source of hydraulic fluid pressure for exclusively supplying pressure fluid to said ram for reciprocating said platen, a plurality of blankholder cylinders in said platen, a blankholder, pistons on said blankholder arranged for reciprocation in said blankholder cylinders, a second and independent source of hydraulic fluid pressure for exclusively supplying pressure fluid to said blankholder cylinders during the retraction stroke of said piston to completely fill said cylinders and provide a constant positive pressure therein to maintain said blankholder separated from said platen, said platen and blankholder being arranged to advance in unison upon a pressing stroke with the blankholder in advance of the die carried by the platen, the fluid pressure in said blankholder cylinders providing for initial pressure contact of the blankholder upon the work in the press and providing means for developing full clamping pressure upon continued advancement of the platen.

3. In combination in a hydraulic press, a platen, ram and main cylinder, a source of hydraulic fluid pressure for exclusively supplying pressure fluid to said ram for reciprocating said platen, a plurality of blankholder cylinders in said platen, a blankholder, pistons on said blankholder arranged for reciprocation in said blankholder cylinders, a second and independent source of hydraulic fluid pressure for exclusively supplying pressure fluid to said blankholder cylinders during the retraction stroke of said piston to completely fill said cylinders and provide a constant positive pressure therein to maintain said blankholder in advance of the die carried by the platen, the fluid pressure in said blankholder cylinders providing for initial pressure contact of the blankholder upon the work in the press and providing for developing full clamping pressure upon continued advancement of the platen, and relief means associated with said blankholder cylinders for relieving pressure developed therein above a predetermined maximum.

4. In combination in a hydraulic press, a platen, ram and main cylinder, a source of hydraulic fluid pressure for exclusively supplying pressure fluid to said ram for reciprocating said platen, a plurality of blankholder cylinders in said platen, a blankholder, pistons on said blankholder arranged for reciprocation in said blankholder cylinders, a constant delivery fluid pump for exclusively supplying pressure fluid to said blankholder cylinders during the retraction stroke of said platen to completely fill said cylinders and provide a constant positive pressure therein to maintain said blankholder separated from said platen, and a pressure relief valve associated with said pump arranged to open a fluid return circuit to said pump to by-pass said blankholder cylinder upon attainment of a predetermined pressure in said cylinders.

5. In combination in a hydraulic press, a platen, ram and main cylinder, a source of hydraulic fluid pressure for exclusively supplying pressure fluid to said ram for reciprocating said platen, a plurality of blankholder cylinders in said platen, a blankholder, pistons on said blankholder arranged for reciprocation in said blankholder cylinders, a constant delivery fluid pump for exclusively supplying pressure fluid to said blankholder cylinders during the retraction stroke of said platen to completely fill said cylinders and provide a constant positive pressure therein

to maintain said blankholder separated from said platen, and a pressure relief valve responsive to the pressure in the blankholder cylinders associated with said pump and arranged to open a fluid return circuit to said pump to by-pass said blankholder cylinder upon attainment of a predetermined pressure in said cylinders.

6. In combination in a hydraulic press, a platen, ram and main cylinder, a source of hydraulic fluid pressure for exclusively supplying pressure fluid to said ram for reciprocating said platen, a plurality of blankholder cylinders in said platen, a blankholder, pistons on said blankholder arranged for reciprocation in said blankholder cylinders, a constant delivery fluid pump for exclusively supplying pressure fluid to said blankholder cylinders during the retraction stroke of said platen to completely fill said cylinders and provide a constant positive pressure therein to maintain said blankholder separated from said platen, and a pressure relief valve responsive to the pressure in the blankholder cylinders associated with said pump and arranged to open a fluid return circuit to said pump to by-pass said blankholder cylinder upon attainment of a predetermined pressure in said cylinders, said platen and blankholder being arranged to advance in unison upon a pressing stroke with the blankholder in advance of the die carried by the platen, the fluid pressure established and maintained in said blankholder cylinders by said pump providing for initial pressure contact of the blankholder upon the work in the press, the pressure fluid providing means for developing full clamping pressure upon continued advancement of the platen, and relief means associated with said blankholder cylinders for relieving pressure developed therein above a predetermined maximum.

7. A method of operating a hydraulic press which consists of applying hydraulic pressure on the press platen to advance the same and a blankholder carried thereby in unison, of applying hydraulic clamping pressure on the blankholder by the continued forward advancement of the press platen after the blankholder has reached a stationary position, of hydraulically retracting the press platen, and of establishing and maintaining a positive predetermined hydraulic pressure in the hydraulic cylinders of the blankholder through means of an independent fluid pressure source upon initiation of the retraction stroke of the platen and until the blankholder again reaches its clamping position.

8. In combination in a hydraulic press, a platen, ram and main cylinder, a source of hydraulic fluid pressure for exclusively supplying pressure fluid to said ram for reciprocating said platen, a plurality of blankholder cylinders in said platen, a blankholder, pistons on said blankholder arranged for reciprocation in said blankholder cylinders, a constant delivery fluid pump for exclusively supplying pressure fluid to said blankholder cylinders during the retraction stroke of said platen to completely fill said cylinders and provide a constant positive pressure therein to maintain said blankholder separated from said platen, and a pressure relief valve associated with said pump arranged to open a fluid return circuit to said pump to by-pass said pump upon attainment of a predetermined pressure in said cylinders.

WALTER ERNST.
